UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,598, dated August 28, 1894.

Application filed July 31, 1894. Serial No. 619,104. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of an irregular arrangement of flowers and leaves of the tulip with 10 skeleton leaves of the tulip as represented in the accompanying drawing. The border or upper portion of the design is also formed of flowers and leaves of the tulip arranged in a continuous horizontal line between an upper

and lower ornamental band as represented in 15 the drawing.

What I claim is—

1. The design for wall paper herein shown and described.
2. In the design for wall paper, the border 20 herein shown and described.

Witness my hand this 28th day of July, 1894.

CHARLES BOOZE.
